UNITED STATES PATENT OFFICE.

OTTO HENRY KOHLHAAS, OF CALUMET, MICHIGAN.

PLANTING AND MARKING MACHINE.

Application filed December 17, 1921. Serial No. 523,007.

To all whom it may concern:

Be it known that I, OTTO H. KOHLHAAS, a citizen of the United States, and resident of Calumet, in the county of Houghton and 5 State of Michigan, have invented a new and Improved Planting and Marking Machine, of which the following is a full, clear, and exact description.

My invention relates to a planting and 10 marking machine, and aims to provide certain new and useful improvements in connection with a device of this character, and more particularly over the construction shown in my prior Patent 1,349,462 dated 15 August 10, 1920.

It is an object of the present invention to provide a device of the character stated in which the marker will embody new construction, and be operated in a novel manner, so 20 that the mark will appear in the exact line with the planted seed. Further this construction will be of such a nature that the marking blade will not be injured upon meeting an obstruction.

25 A further object of this invention is the construction of a device of the character stated in which means will be provided permitting of the driver's wheels traveling over an even surface and consequently insuring 30 an even course to the planter.

Still another object of this invention is the construction of a machine suitable for use as a planter, and marker, in which an adjustment will be provided enabling an operator to perfectly synchronize the operations 35 of the machine in a new row, with respect to the markings and plantings in an adjacent row which has already been completed, this adjustment of the parts being capable of 40 being accomplished by the operator without leaving his seat.

Still another object of this invention is the construction of a machine of the type specified, which shall embody the improvements 45 aforementioned without further embracing an undue complicated structure, thus reducing the cost of manufacture to a minimum, and also at all times insuring a proper operation of the parts.

50 Further objects of this invention will become apparent in the annexed specification taken in connection with the drawings which latter illustrate one practical embodiment of the same, and in which:

55 Figure 1 is a plan view of the machine.

Figure 2 is an enlarged fragmentary side

elevation of certain of the operating parts thereof.

Figure 3 is a transverse sectional view of the parts as shown in Figure 2. 60

Figure 4 is a fragmentary side elevation of the forward portion of the machine, and

Figure 5 is a sectional view of the lower portion of the marker proper.

As in my previous patent afore-referred 65 to, my present machine includes a frame 10 carrying an axle 11, which supports, adjacent its outer ends, a pair of drive wheels 12. Further positioned adjacent the forward end of the frame are a pair of hoppers 13 with 70 which are associated certain mechanism (not shown) which when actuated by means of the rod 14 or any other suitable member, will serve to drop the seeds within the hoppers in the customary and well-known manner. 75

I wish it understood that any suitable mechanism may be employed for connecting the driving axle 11 with the rod 14, but in the embodiment illustrated I have shown the same type of mechanism as was employed in 80 my previous patent. Thus a suitable gear 15 is affixed to the axle 11, and this gear meshes with a corresponding gear 16 associated with the shaft 17, it being noted in this connection that a suitable type of clutch 18 is as 85 sociated with the gear 16 so that the shaft 17 may be disconnected from the axle drive 11. Also a cam disk 19 is affixed to the opposite end of the shaft 17 and this cam disk co- 90 operates with one end of an arm 20, the opposite end of which is affixed to the rod 14 so that when the clutch 18 is engaged and the axle 11 is revolved, the cam disk 19 will 95 actuate the arm 20 thus causing an oscillation of the rod 14 and a corresponding operation of the mechanism of the hoppers 13.

It is to be understood that the foregoing is more or less conventional construction and forms no part of this present invention. However, with a view of providing a marker 100 embodying the improvements set forth in the objects of this invention it will be seen reference being had to Figures 1, 4 and 5, that a subframe 21 is carried by the frame 10, and this sub-frame pivotally supports a 105 bell crank 22, operative connection between one end of the bell crank and the operating rod 14 being accomplished preferably by means of a pair of links 23.

The marker device proper is secured to 110 the opposite end of the bell crank 22 and it will be noted that the objects in connec-

tion with this device are also accomplished by virtue of its particular construction. Thus as has been shown in detail in Figures 4 and 5 the marker preferably includes a tubular body 24 into the lower end of which a rod 25 slidably extends, this rod being partially confined within the tubular body and its movement limited with respect thereto by providing a slot 26 in the said tubular body within which slot a pin 27 rides, the pin being affixed to the rod 25, it being further noted that this rod carries, adjacent its lower end a blade 28, and that a spring 24' has one of its ends secured to the tubular body 24, its opposite end bearing against the rod 25.

Thus assuming that the rod 14 is oscillated it will be appreciated that this oscillation will be transmitted by means of the links 23 to the bell crank 22, and will result in reciprocation on the part of the marker. Also should the blade 28 meet any obstruction it will be obvious that by virtue of the spring the mounting for the same will move upwardly and thus over-ride the obstruction.

Attention being again invited to Figures 1 and 4 it will also be seen that I provide grading plows 29 in advance of the path of travel of the wheels 12, and these plows may be formed with an extension 30 lying in advance of the blade 28, whereby the surface with which this blade cooperates will also be leveled. Thus it will be apparent that the liability of damage occurring to the blade incident to its cooperation over uneven surfaces will be greatly reduced, and also that level surfaces will be provided for the travel of the wheels 12 thus permitting of the machine operating with a maximum of efficiency and insuring neat rows.

Finally it will be understood in connection with a conventional planter that considerable difficulty is experienced incident to the fact that the operator must turn the planter at the end of each row, and when this occurs it is extremely difficult, if not impossible, to insure the operation of the parts of the machine at points in line with previous operations of the same in the previous rows. It is also well understood that it is extremely desirable to have the rows aligning transversely as well as longitudinally, to permit of the subsequent manipu-

lation of the soil, and ultimate gleanings of the harvest. To permit of this result being accomplished it will be seen, reference being had to Figures 1, 2 and 3, that I associate a ratchet wheel 31 with the shaft 17 and a pawl carrying arm 32 is positioned adjacent this ratchet wheel and retained in this position preferably by supporting one of its ends by a spring 33, its opposite end being connected to the inner end of a rockingly mounted lever 34 provided with a treadle 35.

Now assuming that an operator has completed a row and desires to properly align that row with which he is about to proceed, with the markers and planters of the completed row, it will be obvious that he may bring his machine to a point at which the planting and marking devices align with the last mark of the preceding row. Subsequent to this being accomplished (the clutch 18 having been disengaged by means of the lever 36) it will be obvious that the operator may actuate the lever 34 by means of the treadle 35 and this actuation will result in the arm 32 being moved, and incident to the engagement of the pawls of this arm with the teeth of the ratchet wheel 31 the shaft 17 will be turned. This operation may be continued to such a time as the planting and marking mechanism is actuated, and the operator may then engage the clutch 18 and proceed with the work, it being appreciated that incident to the mechanism and operations aforescribed the rows will align transversely as well as longitudinally thus accomplishing the result desired.

From the foregoing it will be understood that all of the objects set forth in the preamble of this specification have been accomplished and that numerous modifications of structure might readily be resorted to without in the least departing from the scope of my claim; which is—

A planting and marking machine including a frame, a pivoted member supported by said frame, an oscillatory rod, interconnected links, one of which is secured to said rod and the other to said pivoted member at one end thereof, and actuated by said rod, and a marking appliance secured to the opposite end of said pivoted member.

OTTO HENRY KOHLHAAS.
